UNITED STATES PATENT OFFICE.

FREDERICK R. EAGLESFIELD, OF NILES, MICHIGAN, ASSIGNOR TO THE KAWNEER COMPANY, OF NILES, MICHIGAN, A CORPORATION OF MICHIGAN.

JOINING MEANS.

Application filed July 2, 1926. Serial No. 120,036.

The present invention relates to joining means, such as bands or rings for joining or connecting sections of a heater or the like.

Among the objects of the invention is to 5 provide a novel joining band structure adapted to fit sections of different sizes without the necessity of carrying different sized bands in stock, but which can be made with the major or main part of the band of a 10 size to fit the smallest heater section and adapted to receive a connected segment to enlarge the band to the larger sizes of sections to be fitted or joined, thus requiring the carrying in stock of only the small 15 segments instead of whole bands of different sizes.

The invention also comprehends the provision of novel means for connecting the ends of a band or of the band and the segments.

Other objects, advantages, capabilities and features are comprehended by the invention as will later appear and are inherently possessed thereby.

25 Referring to the drawings, Fig. 1 is a perspective view of a heater or furnace using bands constructed in accordance with the invention.

30 Fig. 2 is a fragmentary sectional view through a part of the sections of a heater and a band in place.

Fig. 3 is a horizontal sectional view through a part of the band.

35 Fig. 4 is a perspective view of a band showing the construction of the ends thereof.

Fig. 5 is a fragmentary perspective view of partly connected ends of the band or an end of a band with an end of a segment.

40 Fig. 6 is a similar view of the connection shown completed.

And, Fig. 7 is a view in spaced assembly and perspective showing the relation of the ends of a band and an interposed segment, 45 before connection thereof to the ends of the band.

Referring now more in particular to the drawings, the embodiment selected to illustrate the invention is shown as in the form 50 of a band having a main portion 1 preferably of cylindrical form and parted in a plane passing through the axis of the band, the band comprising an intermediate channel portion 2 which acts as a support or separating member between the sections 3

and 4 and 5 of a furnace or heater, and appearing as a rib at the exterior of the heater as clearly shown in Figs. 1 and 2 of the drawings. When in position in the heater, the flanged portions 6 and 7 of the band are located interiorly of the sections of the heater and engaging the interior sides thereof, the inherent resiliency of the band causing the flanges of the band to constantly press against the inner surface of the sections. The rib or channel portion 2 will extend outwardly so that the lower end of a section, such as the lower end 8 will rest upon the top face 9 of the rib 2 and the upper end 10 of the lower section will contact with 65 and support the lower face 11 of the rib 2, as clearly shown in Fig. 2 of the drawings.

The main or major portion of the band is provided with ends 12 and 13 of which the former is preferably provided with apertures 14 formed in the flange portions 6 and 7, and also with adjacent depressed or channeled portions 15 preferably located adjacent to the apertures 14, and the other end 13 being preferably formed with integral 70 tongues or projections 16 extending circumferentially from the ends of the flanged portions 6 and 7, as clearly shown in Fig. 4 of the drawings. The tongues 16 are preferably curved as more clearly shown in Fig. 4 of the drawings, for facilitating the entry of the ends of the tongues into the apertures 14.

When applying the band to a furnace having sections of the smallest size, it is not 90 necessary to use an interposed segment, but the tongues 16 can be directly connected to the other end of the band by the insertion of the ends 17 of the tongues through the apertures 14 so that the body portion of the tongues will fit into the depressed portions 15, and then the ends 17 of the tongues may be laterally bent as shown in Fig. 5 of the drawings, and then hammered over to form the hooked portions 17 as shown in Fig. 6 of the drawings, these hooked portions thus clasping the inner surface of the depressed portions 15 whereby the connection cannot be readily disengaged.

In the event of using the bands in a 100 furnace having sections of larger size, the band may be expanded to form a gap between the ends of the band and a segment 18 may be used to fill this gap. The segment 18 is preferably provided with flange 110

portions 19 and 20 of exactly the same shape as flanges 6 and 7 and also with a channel or rib portion 21 exactly the same as the rib 2. It is to be understood that these segments may be of different lengths to accommodate the particular increase of size in the band desired to fit the particular size of sections of the heater.

The opposite ends of the segments are 10 provided with connecting means respectively the same as at the ends of the major portion of the band, one end being provided with apertures 14 and depressed portions 15 adapted to be connected with the tongues 16 15 of the band in exactly the same manner as previously described when the parts 14 and 15 of the band were connected. The other end of the section has tongues 16 with ends 17 of the tongues curved to enter into the 20 apertures 14 and channel or depressed portions 15 of the adjacent end of the band body portion.

It will be apparent from Fig. 7 of the drawings that the tongues at the right hand 25 end of the segment 18 will enter into and be connected to the end of the main part of the band shown at the right hand side of the segment, and that the tongues 16 on the other end of the main portion of the 30 band and shown at the left hand side of the segment 18 may enter into and be connected to the left hand end of said segment, as shown in said figure. The ends of the tongues may be bent over into the form of 35 a hook in the manner above described in connection with Figs. 5 and 6 of the drawings.

While I have herein described and upon 40 the drawings shown a particular embodiment of the invention, it is to be understood that the latter is not limited thereto but comprehends other constructions, details, features and arrangements of parts without departing from the spirit thereof.

45 Having thus disclosed the invention, I claim:

1. A joining means, comprising a band 50 of circumferential form and having mutually engageable abutting ends, one of said ends having an aperture and a depressed portion, the other of said ends having a tongue adapted to fit into said depressed portion and extend through said aperture.

2. A joining means, comprising a band 55 of circumferential form and having mutually engageable abutting ends, one of said ends having an aperture and a depressed portion, the other of said ends having a tongue adapted to fit into said depressed portion and extend through said aperture, the projecting end portion of said tongue being adapted to be bent to form a hook clasping 60 said depressed portion.

3. A joining means, comprising a band 65 portion and a rib portion both of circumfer-

ential form and parted in an axial plane, and means at the ends of said band portion for mutually connecting said ends together with their ends abutting, said connecting means comprising apertures and depressed portions in one of said ends, and tongues at the other of said ends, said tongues being adapted to fit into said depressed portions and extend through said perforations.

4. A connecting means for joining bands, 70 comprising end portions of a band adapted to be connected together in abutting relation, one of said end portions having an aperture, and a depressed portion adjacent said aperture, the other of said end portions having a projection adapted to extend through said aperture and to fit into said depressed portion, the end of said projection being adapted to be bent to form a hood to clasp said 75 depressed portion.

5. In combination with adjacent edges of 80 upper and lower heater sections, a joining band comprising a sheet-metal split ring having lateral flanges and an intermediate bead adapted to form seats for the edges of the sections, the opposed ends of the split ring being arranged to be drawn together and one of said ends having a tongue lying in the circumferential plane of the flanges of the band and the other end having a laterally depressed portion of a width corresponding to the width of the tongue to snugly receive it, and said depressed portion having a cut-out to permit the projection of the tongue therethrough to fasten the band ends 90 together.

6. In combination with adjacent edges of 95 upper and lower heater sections, a joining band comprising a sheet-metal split ring having lateral flanges and an intermediate bead adapted to form seats for the edges of the sections, the opposed ends of the split ring being arranged to be drawn into abutting relation, and one of said ends having a tongue lying in the circumferential plane of the flanges of the band and the other end having a depressed portion of a width substantially corresponding to the width of the tongue to snugly receive it, said depressed portion having a cut-out to permit the projection of the tongue therethrough to fasten the band ends together in abutting relation.

7. In combination with adjacent edges of 105 upper and lower heater sections, a joining band comprising a sheet-metal split ring having lateral flanges and an intermediate bead adapted to form seats for the edges of the sections, the opposed ends of the split ring being arranged to be drawn into abutting relation, and said ends having mutually 110 engageable tongues and laterally depressed portions of corresponding width, the tongues extending circumferentially of the flanges and the depressed portions extending laterally to accommodate the tongues 115 120 125 130

therein, said depressed portions having cut-outs to permit the tongues to project therethrough for fastening the ends in abutting relation.

8. In combination with adjacent edges of upper and lower heater sections, a joining band comprising a sheet-metal split ring having lateral flanges and an intermediate bead having upper and lower faces outstanding at substantially a right angle to the faces of the flanges of the ring and adapted to form seats for the edges of the sections, the opposed ends of the split ring being arranged to be drawn into abutting relation, and said ends having spaced tongues lying on opposite sides of the bead and in the circumferential plane of the flanges of the band, and having spaced laterally depressed portions on opposite sides of the bead and of a width corresponding to the width of the tongues to snugly receive the tongues, each depressed portion having a cut-out to permit

the projection of the tongue therethrough to fasten the band ends together.

9. A joining means, comprising a band of circumferential form, one end of said joining means being provided with a tongue and the other end provided with a depressed portion of the width of the tongue and extending to the meeting edge to receive the tongue, whereby the ends may meet in true abutting relation.

10. A joining means, comprising a band of circumferential form and having mutually engageable abutting ends, one of said ends having a tongue, the other of said ends having a depressed portion of the width of the tongue and extending to the abutting end, said tongue being adapted to fit into said depressed portion.

In witness whereof, I hereunto subscribe my name to this specification.

FREDERICK R. EAGLESFIELD.
